Design for Patch

№ 2946

PATENTED
MAR 3 1868

W. Stimpfle

Geo. R. Davis
Patentee

Inventor
Horace L. Miller

United States Patent Office.

HORACE C. WILCOX, OF WEST MERIDEN, CONNECTICUT.

Assignor to The Meriden Britannia Co
Design No. 2,946, dated March 3, 1868.

DESIGN FOR A PITCHER.

The Schedule referred to in these Letters Patent and making part of the same.

TO ALL WHOM IT MAY CONCERN:

Be it known that I, HORACE C. WILCOX, of West Meriden, county of New Haven, and State of Connecticut, have invented or produced a new and original Design for a Pitcher; and to enable others skilled in the art to make and use the same, I will proceed to describe by referring to the photographic views, in which the same letters indicate like parts.

In the accompanying photographic views is shown a new and original design for a pitcher. *a* is the body of a pitcher. *b* is a nozzle of a pitcher. *c* is a handle of a pitcher. *d* is a cover configurated with a curvilinear elevation, *e*. *f* is a plain ornamental base, the whole combined to produce a rich and tasty design for a pitcher.

What I claim, and desire to secure by Letters Patent, is—

A new and original design for a pitcher, substantially as shown and described.

HORACE C. WILCOX. [L. S.]
